AIR PUMP AND ACCUMULATOR

James P. Burke, Poland, Ohio, assignor to Murray
M. Fibus and Jerome Marcus, Youngstown,
Ohio

Application July 5, 1951, Serial No. 235,307

3 Claims. (Cl. 222—3)

1

This invention relates to an air pump and accumulator and more particularly to such a device adapted for use in opening clogged drains and the like.

The principal object of the invention is the provision of an improved form of air pump and accumulator.

A further object of the invention is the provision of an air pump and accumulator which may be inexpensively formed and advantageously used due to the novel arrangement of the parts thereof.

A still further object of the invention is the provision of an air pump and accumulator including a normally closed outlet valve and means for opening the outlet valve, operable by applying pressure on the device to simultaneously engage the device on or in a drain opening and to open said valve.

A still further object of the invention is the provision of an air pump and accumulator, the body portion of which acts as a guide for the valve element thereof.

A still further object of the invention is the provision of an air pump and accumulator, the body portion of which comprises an impact extrusion of a shape contributing to the operating efficiency of the device.

The air pump and accumulator disclosed herein comprises an improvement in the art and particularly with respect to the construction and formation and assembly of parts of the device as compared with those devices heretofore known in the art. The air pump and accumulator disclosed herein also differs considerably with respect to the prior art in that it is so formed as to enable it to be engaged in a drain outlet with suitable pressure to effect a seal between the device and the drain outlet and the motion necessary to operate the device applied to the device in the same direction whereby the device remains securely impinged upon or in the drain outlet and avoids the heretofore common tendency of moving away from the drain outlet at the moment of operation.

In the devices heretofore known in the art, the accumulator portions included release valves operable by handles movable away from the point of discharge of the device. In utilizing the devices the tendency of the operator to move the device away from the drain opening at the precise moment of discharge continually occurred with the result that only partially effective results were obtained.

In the present invention the valve arrangement is such that continuous and increasing pressure on the device in the direction of the drain outlet in which the device is positioned is made possible up to and including the moment of discharge of the accumulated air in the device and at such

2

time thereafter as any air pressure exists in the accumulator and/or drain concerned.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

Figure 1 is a side view of the air pump and accumulator with parts broken away.

Figure 2 is a top plan view of the air pump and accumulator taken on line 2—2 of Figure 1.

Figure 3 is a vertical section of the air pump and accumulator taken on line 3—3 of Figure 2.

By referring to the drawings and Figures 1 and 2 in particular it will be seen that the air pump and accumulator comprises an electrical body member 10 in the form of an impact extrusion, the lower portion 11 of which is conical and terminates in a tubular discharge end 12. The uppermost portion 13 of the cylindrical body member 10 is rolled or otherwise suitably shaped to form a shoulder 14 on the inner surface thereof for the reception of a top 15, the uppermost edge of the portion 13 being clinched over the top 15, as best shown in Figure 3 of the drawings, to secure the top 15 in an air-tight manner to the remainder of the device. The top 15 is provided with a central orifice 16 through which a valve rod 17 is positioned, a packing gland assembly 18 being positioned in the orifice 16 about the rod 17 to insure the retention of air pressure in the cylindrical body 10 which forms the accumulator portion of the device.

The lower conical end 11 of the cylindrical body 10 forms an annular valve seat 19 at its point of discharge into the tubular discharge end 12 and a resilient valve member 20 carried on the lower end of the valve rod 17 is provided for engagement with the valve seat 19 to close the outlet communicating with the discharge end 12. A pump cylinder 21 is provided and is positioned within the cylindrical body 10 as best shown in Figure 3 of the drawings. The pump cylinder 21 is provided with an outwardly flanged upper end 22 which registers on a seat 23 formed about a secondary orifice 24 in the top 15 and the pump cylinder 21 is maintained in position by the presence of a nut 25 which in turn is provided with holes 26 for the dual purpose of admitting air to the interior of the pump cylinder 21 and providing means for engagement by a spinner wrench. A piston rod 27 is positioned through a central opening 28 in the nut 25 and is provided with a

piston 29 on its lowermost end and a handle 30 on its uppermost end.

The lowermost end of the pump cylinder 21 takes the form of a tubular discharge pipe 31 over which a rubber check valve 32 is positioned. 5 The rubber check valve 32 is normally closed and air pressure built up within the pump cylinder 21 by reciprocating action of the piston 29 causes the same to open and discharge the air pressure into the accumulator formed by the cylindrical body 10 of the device. An air pressure gauge 33 is positioned on the top 15 and communicates with the interior of the cylindrical body member through an orifice therein so that the air pressure built up within the accumulator portion of the 15 device may be readily determined thereby.

By referring now to the lowermost discharge end 12 of the cylindrical body 10 it will be seen that a resilient fitting 34 is secured thereto and includes a passageway 35 through which the air 20 pressure may be discharged into a drain or the like. The resilient fitting 34 is half-spherical in shape and includes an upstanding annular flange 36 which enables the resilient fitting 34 to be distorted for air-tight registry with various sizes 25 and shapes of drain openings and the like.

In order that the resilient valve member 20 may be moved upwardly and opened at such time as a suitable accumulation of air pressure is built up within the cylindrical body 10 of the device, a handle 37 is provided for imparting movement to the valve rod 17 and is mounted on the top 15 by way of a bracket 38 to which it is pivoted by means of a pivot pin 39. The handle 37 is formed with a projecting end 40 having an opening therein through which the valve rod 17 is passed and adjustment nuts 41 are positioned on the rod 17 above and below the projecting end 40. A spring 42 is caged between the underside of the handle 37 and the 35 upper surface of the bracket 38 and normally urges the handle upwardly and the projection 40 thereof downwardly and thus normally biases the valve 20 toward closed position.

It will thus be seen that at such time as it is desired to operate the device, suitable air pressure is built up within the accumulator comprising the body 10 by the air pump portion and the device then engaged upon the drain outlet or opening with the resilient fitting 34 being held in tight registry therewith by downward pressure brought upon the air pump and accumulator. Similar downward pressure is then exerted on the handle 37 which causes the valve 20 to move upwardly and permits the discharge of the accumulated pressure into the drain, it being observed that at all times the pressure imparted on the device by the operator is in the direction of the drain and opposes the force of the air pressure released thereinto.

Having thus described my invention, what I claim is:

1. In an air pump and accumulator comprising a cylindrical body member having an apertured closure at its upper end and a conical extension at its lower end with a tubular discharge end extending therefrom, and a valve rod positioned centrally of said cylindrical body member and a valve member on the lower end of said valve rod for registry with the conical extension and self-centering in the tubular discharge end, and pump means for introducing air pressure into said cylindrical body member; release means for said valve comprising a handle pivoted to said closure intermediate its ends, one end of said 70 75

handle being engaged upon said valve rod and movable upwardly with the rod when the other end of the handle is moved toward said tubular discharge end of the device, a spring engaged by the said closure in the other end of said handle, said spring being of sufficient stiffness to hold the air pump and accumulator strongly against a clogged drain.

2. An air pump and accumulator comprising 10 a hollow body member formed as an impact extrusion with a conical end having a tubular discharge end extending therebeyond defining a valve seat, the opposite end of said hollow body member having an annular rolled shoulder and a closure disc seated thereon, the outermost end of the hollow body member being clinched over said closure disc, said closure disc having spaced orifices therein, an air pump positioned in the hollow body member through one of said orifices and an apertured nut engaged in said orifice and holding said pump in position, a piston rod of said pump passing through said apertured nut, a valve rod positioned through another orifice in said closure disc, a valve element on the innermost end of said valve rod for self-alignment with the valve seat in the outermost portion of the conical end portion of the body member, a bracket positioned on said closure disc and a handle pivoted to said bracket intermediate its ends, one end of said handle adjustably secured to said valve rod, and spring means of sufficient stiffness to hold the device securely against a drain biasing the other end of the handle away from the closure disc whereby movement of one portion of the handle toward the closure disc moves the portion thereof engaged upon the valve rod away from said closure disc and the valve element away from the valve seat in the conical end portion.

3. In a drain cleaning air pump and accumulator having a closed cylindrical body provided with an internal air pump and an external pressure gauge for building up a preselected air pressure within said cylindrical body and a release valve for controlling the discharge of the air under pressure from said cylindrical body, the discharge end of said cylindrical body being conical and forming a valve seat, a valve rod extending from said discharge valve and having an end projected from said closed cylindrical body, a lever pivoted intermediate its ends on said cylindrical body, one end of said lever connected to said valve rod and spring means between said cylindrical body and the other end of said lever normally urging said rod and said discharge valve into 50 55 60 65 said conical end of said cylindrical body, said spring means being of sufficient stiffness to forcibly seat the device securely against a drain whereby movement of the spring loaded end of said lever toward said cylindrical body imparts outward movement to said valve rod and said discharge valve with respect to the conical end of said cylindrical body.

JAMES P. BURKE.
